UNITED STATES PATENT OFFICE.

JESSE GILBRETH FALLS, OF MEMPHIS, TENNESSEE.

ICE-CREAM FREEZER.

SPECIFICATION forming part of Letters Patent No. 436,309, dated September 9, 1890.

Application filed July 5, 1890. Serial No. 357,857. (No model.)

To all whom it may concern:

Be it known that I, JESSE GILBRETH FALLS, a citizen of the United States, residing at Memphis, in the county of Shelby and State 5 of Tennessee, have invented certain new and useful Improvements in Refrigerators; and I do hereby declare the following to be a full, clear, and exact description of the invention, such as will enable others skilled in the art 10 to which it appertains to make and use the same.

My invention relates to improvements in refrigerators of the class known as "revolving cylinder ice-cream freezers," and it consists 15 in various details of construction whereby I am enabled to effect the freezing more rapidly and economically than has heretofore been accomplished.

The objects of my invention are to supply 20 a machine compact in form, inexpensive to manufacture and operate, and which will enable any person possessed of the requisite materials to prepare ice-cream, frozen custard, sherbet, &c., without delay, such as is involved in the manipulation of an ordinary 25 ice-cream freezer, and with very little effort or labor; to make a machine especially adapted to the use of families and small parties, where rapid action and little preliminary trouble in 30 making preparations would be considered the most valuable features of the device. These objects I attain by means of the mechanism illustrated in the accompanying drawings, in which—

35 Figure 1 is a side elevation of the machine with the side of the case partly broken away to show the parts within. Fig. 2 is an end elevation with a portion of the case removed to show the cylinder and scraper. Fig. 3 is a 40 reverse side elevation showing the drive-gearing. Fig. 4 is a plan with the cover of the case removed. Fig. 5 is a perspective view of the scraper.

The cylinder A is made of sheet metal and 45 is intended to hold the refrigerating mixture of ice and salt, &c., which is introduced through the opening a until the cylinder is substantially filled. It is supported on suitable journals b b', resting in bearings in the 50 sides of the case B, and is rotated by means

of a gear-wheel C, journaled in the lower or bottom half of the case and actuated by a crank c', as best shown in Figs. 3 and 4. The material to be frozen is poured into the pan D, which is for convenience in this operation 55 partially withdrawn through the open end of the case, and after being filled is returned to the position shown. I am thus enabled to dispense with a funnel for introducing the material and to avoid an opening in the case. 60

The device is best operated by setting it upon a table with the open end projecting slightly over the edge thereof, and the material removed by the scraper is caught in a vessel held on the knees of the operator, or 65 the pan D may be partially withdrawn through the case so that the frozen material will fall back into it as it is removed by the scraper.

The operation is as follows: The cover of the case is taken off and the cylinder removed 70 from the case, the cap unscrewed and the cylinder filled with crushed ice and common salt, the cap replaced and tightly screwed up and the cylinder carefully freed from all traces of salt which may have adhered to its surface, 75 and is then replaced in the case, the cover secured and door G closed. In this condition it can be kept in readiness for instant use, and the ice unmelted for several hours. In using, the door G is raised and secured, the 80 pan D partially drawn out through the open end of the case, the cream or other material introduced, and the cylinder slowly rotated by turning the crank, the cream at once freezing in a layer on the surface of the cylinder, 85 and is removed by the scraper E, falling into the receptacle provided for the purpose, as heretofore explained. The scraper E is held in position by wire springs e, fixed in the end of the case, one of these being shown in Fig. 90 1. These springs are independent of each other, and their inturned ends e' take into lugs on the sides of the scraper and press its sharp edge against the cylinder, and its downwardly-extending side pieces against the end 95 of the bottom of the case, so that it is yieldingly pressed against the face of the cylinder and readily detachable when the cylinder is removed from the case, whence it results that all parts may be easily removed for the pur- 100

- pose of cleansing them. The side extensions of the scraper are separated, so that the pan can be withdrawn between them, and the space below the scraper and above the pan is 5 such that the operator can while at work inspect the pan and see when the contents require renewal or when the process is completed. The door G, hinged to the end of the case, is to be kept closed when the machine 10 is not in use, and is fitted over the scraper and springs, so as to form a close joint. The cover is also made to fit closely, so that there are no openings to admit air when the device is not being used.
- 15 The bottom of the case is shorter than the sides and top thereof, thus giving the scraper a vertical position nearly tangential to the cylinder. By this construction I avoid the troublesome clinging of masses of frozen material to the scraper, as results when the latter is inclined, and the material falls freely, clear 20 of all parts of the machine, into the receptacle provided for the purpose.
- 25 The gear-wheel C and journal b' will preferably be cast in one piece, and I propose making it of brass or zinc, so that it can be soldered directly to the side of the cylinder; but it may be made of cast-iron and galvanized and soldered or riveted to the cylinder.
- 30 The journal b may in like manner be made

of any suitable material and be attached in any preferred manner.

Having thus described my invention, I claim—

1. In a refrigerator of the character described, the scraper E, having the narrow edged portion and the downwardly-extending side pieces, thus leaving a recess below the scraper and between the arms for access to the interior, substantially as described. 35

2. In a refrigerator of the character described, the case having the shortened bottom, and the scraper having the side extensions bearing against said bottom, in combination with the pan made narrower than the 45 space between the arms of the scraper and adapted to being partially withdrawn through said space, as and for the purpose specified.

3. In a refrigerator of the character described, the scraper having the lug-bearings, 50 in combination with the springs, whereby the scraper is removably held in place against the cylinder, as shown and described.

In testimony whereof I affix my signature in presence of two witnesses.

JESSE GILBRETH FALLS.
